GAS COCK

Benjamin E. Meacham, Cleveland, and William Lotter, Parma, Ohio, assignors to American Stove Company, St. Louis, Mo., a corporation of New Jersey

Application November 3, 1936, Serial No. 109,018

4 Claims. (Cl. 277—41)

This invention pertains to gas cocks and comprises an improvement, in certain respects, upon the gas cock appearing in the copending application of Benjamin E. Meacham, Serial No. 74,384.

5 The present gas cock has been devised for use in connection with cooking ranges and in connection with their operation it has been found that it is often highly desirable to provide a device by means of which close control of the flow 10 of the fuel to the gas burners can be obtained. Although the control of fuel to a gas burner is specifically above referred to it is to be readily understood that the present cock is not necessarily limited in use to the control of gas but could 15 be used to control the flow of other fluids or liquids.

A gas cock affording a close fuel control such as does the present cock is particularly desirable for use with closed or solid top cooking ranges such as are used in hotels, restaurants, hospitals 20 and similar places, due to the fact that such ranges are operated at high temperatures usually only at meal hours yet throughout practically the entire day and night too it is desirable to maintain the top of the range warm, and to accomplish this it is necessary to operate the heating burners with a low flame or fire.

Past experience has proven that where a gas cock of the ordinary and conventional rotary plug type is provided or utilized it is particularly 30 difficult to obtain the close control of the fuel to the burners which is necessary and desirable and consequently in the present device there is provided not only a rotary plug type of gas cock but in combination therewith a supplemental 35 valve or cock control in the form of a secondary or supplemental control in addition to the main rotary plug valve.

From the foregoing it will be therefore apparent that one of the primary objects of the 40 present invention is the provision of a valve or cock by which a close control of the fuel to a burner can be obtained.

A further object of the invention is the provision of a cock or valve having the above referred to attributes which is simple and cheap of construction yet highly efficient in operation.

Another and still further object of the invention is the provision of a gas cock having the 50 above referred to and enumerated attributes and which is leak-proof and which eliminates use of all forms of packing.

A still further object of the invention is the provision of a fuel control cock having a novel

drive connection between the operating handle and the main and supplemental fuel control valves of said cock.

Other specific objects, novel features of construction and improved results of the invention will appear in more detail in the following description when read in the light of the accompanying drawing.

In the drawing:

Fig. 1 is a vertical sectional view through the 10 improved cock.

Fig. 2 is a vertical sectional view taken at right angles to Fig. 1, on the line 2—2 of said figure.

Fig. 3 is a vertical sectional view taken on the line 3—3 of Fig. 2.

Having reference now to the drawing which illustrates a preferred embodiment of the present invention and in which like parts are designated by similar reference numerals throughout the description and the drawing, A designates a valve housing or fitting which is intended to constitute a part of the fuel line from a fuel supply to the burners utilizing the said fuel and as a consequence this member has its inlet end 1 suitably threaded as at 2 for connection with a suitable source of fuel supply while its opposite outlet end 3 is suitably threaded as at 4 for connection with a pipe or manifold for conveying the fuel to the burner or burners intended to utilize said fuel.

Intermediate the fuel inlet 1 and the fuel outlet 3 the fitting is enlarged to form an open ended tubular portion having its inner face beveled, as clearly indicated at 5 to rotatably receive a tapered plug or main valve B the inner reduced end of which is further reduced to provide a shaft 6 which extends outwardly beyond the small end of the tubular part 7 of the fitting.

This shaft 6 has flattened sides and carries a washer or plate 8 having therein an opening having flattened sides so that said washer rotates with the shaft. At its outer end the shaft is threaded and carries a main nut 9 and a lock nut 10 which serve as an abutment for one end of a spring 11 which surrounds the shaft while the other end of the spring abuts the plate or washer 8 and holds said washer against the end of the tubular portion of the fitting under resilient spring tension. Thus it will be seen that the washer is a closure for the small or reduced end 50 of the tube-like portion of the fitting and additionally this washer acts as a stop to limit the rotative movement of the main plug valve. To accomplish this function the plate or disc has on its peripheral edge an arc-shaped cut-out portion 55

and the shoulders at the ends of said cut-out portion are adapted to engage the outwardly extending stop 12 which forms a part of the tubular portion 7 of the fitting. The engagement between the washer and the stop is clearly illustrated in Figure 1 of the drawing. This manner of forming a stop is more or less conventional and is quite similar to that illustrated and described in the aforementioned copending 10 Meacham application Serial Number 74,384. This construction affords a means for limiting the movement of the main rotary valve so as to assure that the operator of the device can definitely fully open and fully close the main plug valve B.

The plug valve has a transverse opening or bore 13 which through rotation of the plug can, at will, be made to register with the inlet and outlet pipes 1 and 3 of the fitting. This main plug valve 20 is elongated to extend well out beyond the open large end of the tubular portion 7 of the fitting and is hollow so that in reality it forms a tube having an open outer end 14 and inner closed end 15. At its outer end the plug is formed 25 with a pair of circumferential flanges arranged in spaced relation and constituting oppositely positioned wings or lugs 16 and 17 which extend at right angles to the main body plug. Interiorly the plug at its open end is provided with a chamber 18 and between this chamber and the fuel passageway 13 of the plug the interior of the plug is tapered, as clearly appears at 19 while beyond the transverse fuel passageway 10 the plug is 30 provided with a second chamber 20 which terminates in the aforementioned bottom 15.

The secondary valve, which we term a butterfly valve, is designated as an entirety by C and is positioned and rotatable within the hollow main rotary plug valve B. This plug valve 40 comprises a tapered portion 21 of the proper length and diameter to enter and freely rotate within the tapered portion 19 of the main plug valve. From the tapered cylindrical portion there extends outwardly a reduced shaft portion 22 which 45 is disposed within the chamber 18 and from this shaft extends a second shaft 23 which extends outwardly through and beyond the open end of the main plug valve. The shaft 23 is an angular shaft and has one of its corners cut away as appears at 24. From the other and reduced end of the tapered cylindrical plug-like portion of the butterfly valve there extends a disc or shutter 25 having therein a small passageway 26. This shutter is of a size to extend from one side to 50 the other of the passageway 13 of the main plug valve. At its inner-most end or side this shutter terminates in a circular disc or plug 27 of the proper diameter to enter and rotate within the innermost chamber 20 of the main plug valve.

Both the primary and secondary valve are 55 operated by a hand knob or wheel D which has a hub portion 27 terminating in a plate or disc 28. The plate and hub are provided centrally with an opening 29 having the same cross sectional configuration as that of the butterfly valve shaft 23 so that said shaft can enter the opening and provide a driving connection between the hand wheel and the butterfly valve. Due to the flattened corner of the shaft and a corresponding flattened 60 wall in the opening 29 proper engagement of the shaft with the operating handle is assured. At its under side the disc is provided with oppositely disposed and outwardly extending wings or lugs 30 and 31 and when the operating handle is in proper operating position these lugs extend

downwardly into the spaces between the lugs or wings 16 and 17 carried by the outer open end of the main plug valve. Inasmuch as the space between the wings 16 and 17 is larger than the combined size of the lugs 30 and 31 it will be understood that when the handle is rotated in a clockwise direction, see Fig. 3 of the drawing, considerable rotation will take place before there is driving connection made between the lugs of the operating handle and the lugs of the main plug valve.

A U-shaped collar or fitting E together with a nut 32 are utilized to secure the operating wheel in proper operating position. It will be seen that the bottom 33 of this fitting engages the under sides of the plug valve wings 16 and 17 while its other leg 34 extends outwardly at right angles and is internally threaded to receive the threaded peripheral edge 28 of the wheel disc as clearly appears at 35. It is understood of course that the U-shaped fitting E is of a proper diameter to receive the disc 28 and when said disc has been properly positioned it is secured or locked by the aforementioned nut 32.

The coil spring 11 assures that the tapered main plug valve B is maintained within its tapered seat under sufficient resilient tension to prevent the leakage of fuel and a coil spring 36 is positioned within the chamber 18 and serves to exert resilient pressure upon the plug portion 21 of the butterfly valve C to assure that this tapered plug portion maintains a leakage-proof connection or engagement with its tapered seat.

Lubrication for the main rotary plug valve is obtained by providing the tapered portion of said valve with grease grooves 37 and the tapered plug portion of the butterfly valve is similarly provided with grease or lubricant-receiving grooves 38.

A pointer 39 adapted to move over an indicating dial (not shown) is suitably secured as at 40 to the hub portion 27 of the operating wheel and serves the purpose of visibly indicating the positioning of the parts.

Operation.—Assuming the main valve to be 45 closed rotation of the hand operating wheel will rotate the main plug valve to a position where its transverse port 13 is in alignment with the inlets and outlets 1 and 3 of the fitting. When the main plug valve is open the secondary or 50 butterfly valve is closed as clearly appears in Fig. 1 of the drawing, from which it will be seen that the shutter or disc 25 of this valve is transverse the bore 13 of the main plug valve. When the parts are in this position a very limited 55 amount of fuel reaches the outlet 3 through the small orifice 26 in the butterfly disc. Rotation of the operating wheel in the reverse direction however will permit any desired positioning or adjustment of the butterfly disc 25 in respect to the bore 13 through the main plug valve and by this manipulation it will be clearly understood that a close control of the fuel passing to the outlet 3 can be obtained.

The drive connection between the operating wheel D and the butterfly valve is positive at all times through the squared shaft 23 but it will be readily understood from the foregoing description that there is a lost-motion drive connection between the wings 30 and 31 of the operating handle disc and the wings 16 and 17 of the main plug valve with the result that when the main plug valve has been rotated to a fully open position the operating handle can be revolved in the 75

reverse direction for adjusting the shutter of the butterfly valve without in any way affecting the previously adjusted position of the main plug valve. Continuing the rotation however of the 5 operating handle D in a reverse direction will bring the wings of the operating handle into engagement with the wings of the main rotary plug valve to permit that valve to be moved to a closed position when it is no longer desired to operate 10 the burners.

From the foregoing description and from an examination of the drawing it will be seen that the present cock is of a much more simplified construction than that appearing in the Meacham 15 copending application heretofore referred to, and that as a consequence it is cheaper to manufacture and the possibility of inaccurate operation or trouble or maintenance is materially reduced by reason of this simplified construction.

20 We claim:

1. An improved cock, comprising a housing having a passageway therethrough, an open ended chamber in said housing intermediate the length of said housing passageway and having its inner 25 walls tapered to provide a conical valve seat, a hollow tapered plug valve in said seat and provided with a passageway adapted for communication with the housing passageway at each side of said chamber, said plug valve interiorly provided with a conical shaped chamber, a secondary valve having a conical shaped portion seated 30 within the conical chamber of the main valve and provided with a shutter adapted to open and close the passageway of the main valve, means 35 to hold said main valve upon its conical seat under resilient tension, means to hold the conical portion of the secondary valve within its conical seat under resilient tension, and operating means to rotate said main plug valve and 40 said secondary valve in respect to the housing, for the purpose described.

2. An improved cock, comprising a housing having a passageway therethrough, an open ended chamber in said housing intermediate the 45 length of said housing passageway and having its inner walls tapered to provide a conical valve seat, a hollow tapered plug valve in said seat and provided with a passageway adapted for communication with the housing passageway at each 50 side of said chamber, said plug valve interiorly provided with a conical shaped chamber, a sec-

ondary valve having a conical shaped portion seated within the conical chamber of the main valve and provided with a shutter adapted to open and close the passageway of the main valve, means to hold said main valve upon its conical seat under resilient tension, means to hold the conical portion of the secondary valve within its conical seat under resilient tension, and a common operating means to rotate said main plug valve and said secondary valve in respect to the housing and in respect to one another, for 10 the purpose described.

3. An improved cock, comprising a housing having a passageway therethrough and an open ended chamber intermediate the length of said 15 passageway provided with tapered walls to form a conical valve seat, an elongated hollow primary valve having a tapered plug portion engaging the conical seat of said chamber and provided with a passageway adapted for communication with the housing passageway at each side of said chamber, said valve at its ends provided with a pair of outwardly extending spaced apart wings and interiorly provided with a conical shaped 20 chamber, a secondary valve within said primary valve and having a conical shaped portion seated within the conical chamber of the primary valve and provided with a shutter adapted to open and close the passageway of the primary valve, means 25 to hold said main valve upon its conical seat under resilient tension and to hold the conical portion of the secondary valve within its conical seat under resilient tension, an operating handle 30 provided with wings extending into the spaces between the wings of said primary valve, said 35 operating handle further provided with positive drive connection with said secondary valve, and said operating handle constituting a common means for rotating said main plug valve and said secondary valve in respect to the housing and the 40 secondary valve in respect to the primary valve, for the purpose described.

4. An improved cock constructed as defined in claim 3, wherein the drive connection between the operating handle and the secondary valve is 45 such as to guarantee that the position of the operating handle in respect to the secondary valve is always the same.

BENJAMIN E. MEACHAM. 50
